INVENTOR
George C. Cheek.

BY Chas. Edmund,

ATTORNEY

UNITED STATES PATENT OFFICE.

GEORGE C. CHEEK, OF SACRAMENTO, CALIFORNIA.

GARBAGE COLLECTOR AND RECEIVER.

1,358,618.

Specification of Letters Patent. Patented Nov. 9, 1920.

Application filed January 7, 1920. Serial No. 349,950.

To all whom it may concern:

Be it known that I, GEORGE C. CHEEK, a citizen of the United States, residing at Sacramento, in the county of Sacramento 5 and State of California, have invented new and useful Improvements in Garbage Collectors and Receivers, of which the following is a specification.

This invention relates to a garbage collector and receiver.

One of the objects of the present invention is to provide a simple, cheaply manufactured and easily installed receiving and collecting system for garbage which is particularly adapted for installation in apartment houses and the like. The garbage collector consists of a main receptacle placed where it may be emptied from time to time either from the street or the yard. It also consists of a plurality of receivers preferably located one in each kitchen and a chute connecting each receiver with the main collecting receptacle.

Another object of the invention is to provide a garbage receptacle so constructed that all liquid matter may be drained off and conveyed to the sewer.

Another object of the invention is to provide a novel support for the receiver which permits it to be raised and lowered within a housing and to be pulled forward and tilted when the garbage is removed.

Further objects will hereinafter appear.

The invention consists of the parts and the construction, combination and arrangement of parts as hereinafter more fully described and claimed, having reference to the accompanying drawings, in which—

Figure 1 is a diagrammatic view showing the relative position of the different parts of the system.

Fig. 2 is a front view of the main receiving container.

Fig. 3 is a vertical cross section taken on line 3—3 at right angles to Fig. 2.

Referring to the drawings in detail, A indicates in general a main collecting receptacle, which in this instance is mounted within a housing 2 forming part of the building structure. This housing is preferably positioned so that the container may be emptied either from the street or the yard and access to the container may only be obtained by opening a door 3 which is normally closed and secured by a lock 4.

The receptacle consists of the main con-

tainer A, interiorly of which is mounted a strainer 5, constructed in the form of a wire basket spaced from the main walls of the container or a tapering metal cylinder which is perforated. The receptacle A and the strainer therein are carried by a pan 6, on the lower side of which is formed a discharge pipe 7. This pipe has a sliding fit into a sewer pipe 8 and a stuffing box or other suitable packing interposed between the two forms a leak-proof point. Leading to the housing 2 is a chute 9. This chute leads to a receiver 10, preferably located in the kitchen of one of the apartments; and where several apartments employ receivers of a similar nature it is obvious that all the chutes may converge just above the housing 2 so as to enter through a single spout 11, under which the main receptacle A is placed, or each chute 9 may connect with a separate receptacle A.

The pan supporting the receptacle is mounted in the outer end of a bell-crank lever 12, which is pivotally mounted interiorly of the housing shown at 13. The opposite end of this bell-crank lever is connected with a hand lever 14 which is provided with a handle 15 and a latch 16 which is adapted to engage a pin 17 when the pan is raised, as shown in Fig. 3.

If the receptacle or main receiver A is full and it is desired to empty the same, it will first be necessary to open the door 3. The handle 14 is then lifted out of engagement with the pin 17 and pulled in a forward direction. This permits the pan to drop into the lowered position shown by the dotted lines at 6^a and the main receptacle to drop to the dotted line position shown at A'; this position being controlled by a pair of pins 18, one on each side of the receptacle which project into L-shaped slots 19 formed in the sides of the housing. The receptacle is provided with a handle 20 on its forward side and it may, therefore, be pulled in a forward direction when the pins engage the horizontal portions of the slots 19. It may also be pulled clear forward into the dotted line position 20^a and may here be tilted and emptied. It cannot at any time be removed as the pins engaging the slots 19 prevent such removal, it being one of the objects of the invention to prevent the garbage collector from stealing or otherwise removing the main receiver.

The receiver when empty is merely shoved

back into alignment with the pan, the lever is then pushed back by means of the handle 15 until the pan 6 engages the receptacle and lifts it to the full line position shown in Fig. 3. Dropping of the handle brings it into engagement with the pin 17, thus locking the pan and the receptacle in the elevated position shown in register with the spout 11.

10 A garbage receiving and collecting system arranged in the manner here shown is particularly adapted for houses containing a number of separate apartments or dwellings; first, because it saves the housewife or servant the inconvenience of stepping outside to dispose of the garbage, and second, because it positively does away with a number of garbage cans and the trouble of emptying the same. It is furthermore more 15 sanitary as the garbage after once being placed in the receiver is immediately conveyed to a main collecting receptacle which is housed in and covered up in such a manner that flies or vermin cannot possible feed thereon, nor can odors of any kind escape 20 or enter the yard or the dwelling proper.

25 Flushing of the several chutes leading to the main collecting receptacle with water may be resorted to from time to time as it will prevent clogging of the chutes and will always maintain the same in a clean and sanitary condition. Flushing or cleaning in this manner is not objectionable in the present instance as all water or liquid matter conveyed to the main receptacle will drain away from the garbage and will finally enter the sewer through the pipe 8.

30 The device as a whole is simple, cheap to manufacture and is particularly adapted for installation in large buildings as the chutes may be placed within the walls and directed to any convenient point where it is desired to collect and remove the garbage. No one but an authorized collector can open the 35 door 3 as this is always locked, and as only a certain collector has a key, it is obvious that the disposal of garbage will be taken care of and by the right collector.

40 The housing 2 may be provided with brooms, rakes and other implements for the proper cleaning of the collecting receptacle and the surrounding space, and while the several parts employed are preferably constructed of galvanized metal I wish it understood that the specific construction involved may be varied within the scope of the appended claims and as the experience and judgment of the manufacturer may dictate.

45 60 Having thus described my invention, what I claim and desire to secure by Letters Patent is—

55 1. In a device of the character described, a main collecting receptacle, a support for said receptacle, means for raising and low-

ering said support, and an independent guide for the receptacle in which it is vertically and horizontally slideable, said receptacle being adapted to be tilted when moved or slid to its horizontal position.

2. In a device of the character described, a main collecting receptacle and a housing therefor, a support for said receptacle, means for raising and lowering said support, an independent guide for the receptacle including an L-shaped slot in the opposite walls of the housing, and a pair of pins, one on each side of the receptacle, entering said slots, said pins permitting the receptacle to be moved vertically and in a forward direction 75 and also permitting tilting of the receptacle when in a forward position.

3. A garbage collecting apparatus comprising in combination a main receiver having a perforated bottom and an interior perforated strainer, a pan in which the receiver is supported, said pan having a downwardly tubular extension, a fixed conducting pipe in which the extension is slideable, a bell-crank lever, one arm of which connects with the pan, a reciprocal rod connecting with the other lever arm, and means to detachably engage said arm to retain the pan and receiver in an elevated or depressed position. 85

4. In a device of the character described, a main collecting receptacle, a pan forming a support for said receptacle, means for raising and lowering the pan, and means forming an independent guide and support for the collecting receptacle, said means 95 permitting vertical and longitudinal movement of the receptacle and tilting thereof.

5. In a device of the character described a main collecting receptacle, a pan forming a support for said receptacle, a bell-crank supporting said pan, a hand lever adapted to swing the bell-crank to raise and lower the pan, a pin on each side of the receptacle and a support having slots formed therein into which the pins project, said support 105 adapted to carry the receptacle independently of the pan when this is lowered, said slots and pins also permitting longitudinal movement of the receptacle to a forward position and tilting of the receptacle in said forward position.

6. In a device of the character described a main collecting receptacle, a pan forming a support for said receptacle, a bell-crank supporting said pan, a hand lever adapted to swing the bell-crank to raise and lower the pan, a pin on each side of the receptacle, a support having slots formed therein into which the pins project, said support 110 adapted to carry the receptacle independently of the pan when this is lowered, said slots and pins also permitting longitudinal movement of the receptacle to a forward position and tilting of the receptacle in said forward position, and means for locking the 115 120 125 130

hand lever when the bell-crank and pan supported thereby assumes a raised position.

7. In a device of the character described a main collecting receptacle, a pan forming 5 a support for said receptacle, a bell-crank supporting said pan, a hand lever adapted to swing the bell-crank to raise and lower the pan, a pin on each side of the receptacle, a support having slots formed therein into 10 which the pins project, said support adapted to carry the receptacle independently of the pan when this is lowered, said slots and pins also permitting longitudinal movement of the receptacle to a forward position and

tilting of the receptacle in said forward position, means for locking the hand lever when the bell-crank and pan supported thereby assumes a raised position, means for draining the contents of the main receptacle and a discharge connection on the pan for 20 removing the drainage.

In testimony whereof I have hereunto set my hand in the presence of two subscribing witnesses.

GEORGE C. CHEEK.
